FACSIMILE MACHINE

Austin G. Cooley, New York, N. Y., assignor to
 Times Telephoto Equipment Inc., New York,
 N. Y., a corporation of New York

Application November 7, 1941, Serial No. 418,172

5 Claims. (Cl. 178—6.6)

This invention relates to facsimile machines and more especially to facsimile machines of the tape transmission and tape recording type.

A principal object of the invention is to provide a unitary tape facsimile transmitting and receiving machine which is specially designed to be of extreme simplicity and rugged construction and assembly.

Another object is to provide a unitary facsimile transmitting and recording machine which is compact and of light weight.

Another object is to provide an improved tape feed mechanism.

A feature of the invention relates to a simplified scanning head for a tape facsimile transmitter.

Another feature relates to an improved tape facsimile recorder for producing a multiple reproduction of a transmitted facsimile.

A further feature relates to an improved tape recorder head of the intersecting edge recorder type.

A further feature relates to an improved actuating mechanism for the recording head of a facsimile recorder of the rotatable platen and co-operating straight edge type.

A still further feature relates to the novel organization, arrangement and relative location of parts which cooperate to form a simple, cheap and rugged facsimile transmitter-recorder machine.

Other features and advantages not specifically enumerated will be apparent after a consideration of the following detailed descriptions and the appended claims.

In the drawings illustrating one construction of machine which has demonstrated its utility for the purposes intended,

Fig. 1 is a front elevational view of the working parts of my improved tape transmitter-recorder machine with certain cover plates removed.

Fig. 2 is a left-hand side view of Fig. 1.

Fig. 3 is a right-hand side view of Fig. 1.

Fig. 4 is a detailed sectional view of part of Fig. 1, taken along the line 4—4 thereof.

Fig. 5 is a sectional view of Fig. 4 taken along the line 5—5 thereof.

Fig. 6 is a sectional view of Fig. 2 taken along the line 6—6 thereof.

Figs. 7, 8 and 9 are respective sectional views taken along the lines 7—7, 8—8, 9—9 of Fig. 6.

Fig. 10 is an enlarged detailed view of part of the recorder bar actuating mechanism.

Fig. 11 is a detailed view of the clutch of Fig. 1.

Fig. 12 is a developed or flattened-out diagram-

matic representation of the scanning end of the scanning drum.

Fig. 13 is a similar developed or flattened-out diagrammatic view of the recording drum.

Fig. 14 represents a short section of message tape used for transmission, while

Fig. 15 represents the corresponding tape as reproduced according to the invention.

Referring to Fig. 1, there is shown a unitary

10 facsimile transmitter and recorder machine for transmitting and recording intelligence or other subject matter embodied in tape or web form. The machine comprises a base plate 1 to which are bolted at opposite ends the vertical walls 2 and 3. Members 2 and 3 are also united by a horizontal platform 4 on which is suitably fastened the main driving motor M. The left-hand end 5 of the motor shaft has fastened thereto by set screws 6 (Fig. 6) the perforated opaque scanning drum 7, while the right-hand end 8 of the motor shaft has fastened thereto the recording drum or platen 9. The scanning drum 7 is in the form of an elongated metal cylinder having three sets 10, 11, 12, of scanning perforations (Fig. 12). Fig. 12 represents the drum 7 in developed or planar form from which it will be seen that the sets of perforations, while they extend substantially the same distance along the drum, are so arranged that during each complete revolution of the drum, each perforation scans a different point on a given line across the scanning field 13. Thus in the example shown, there are twenty perforations in each set, and the tape moves continuously at such a rate so that each

20 elemental transverse line of the tape is scanned in twenty successive elemental areas of approximately 0.0001 square inch. Thus during each revolution of the drum, three successive elemental transverse strips of the tape are scanned. In order to select the successive linear strips of the tape for scanning, there is provided a tubular opaque shield 14 which is telescoped over the stationary bearing hub 15 of the motor. Shield 14

30 may be held on hub 15 by a set screw or otherwise rigidly fastened thereto. The left-hand end of shield 14 has a slot 16 of a length slightly greater than the width of the scanning field to be covered by the scanning perforations in the drum. The slot 16 has a width approximately the same as the diameter of the individual scanning perforations and this slot extends parallel to the axis of the drum rotation.

Also rigidly fastened to the shoulder 17 on the 40 motor frame, e. g., by means of clamping ring 18

and screw 19, is a tubular metal housing 20 having an inwardly extending annular flange 21 adjacent its left-hand end. Fastened to flange 21 by means of screws 22, is a supporting base 23 for the photoelectric cell 30. Cell 30 may be of any well-known type consisting of a glass bulb having on the interior a photoelectric cathode and a co-operating anode. The bulb can be rigidly held in the base 23 in any suitable way, for example by cement or the like. The base 23 has a pair of arcuate slots 24 through which the fastening screws 22 extend so that by loosening the screws 22 the base can be rotated to align the photo-cell electrodes with the slot 16. A closure member 25 in the form of an insulating disc can also be attached to the base 23 by means of screws 26. The photo cell is therefore completely protected from extraneous light except that which enters through the slot 16 and the scanning perforations in drum 7. In order to allow for adjustment, the housing 20 is provided with a window 33 which is much wider than the slot 16, the window 33 having a length approximately equal to the width of the scanning field.

Shield 14 and housing 20 have openings 34, 35, (Fig. 9) to permit the passage of the cross shaft 36 and its worm-wheel 37 so that the latter meshes with worm 38 on motor shaft 5. Shaft 36 is supported for rotation in suitable bearings in bearing blocks 39, 40, carried by wall 2, it being understood that platform 4 has an opening to permit the shaft 36 to pass freely therethrough. At its lower end, shaft 36 carries a worm 41 in mesh with a worm-wheel 42 fastened to counter-shaft 43, which is mounted for rotation in suitable bearing blocks 44, 45 fastened to walls 2 and 3 respectively. Shaft 43 is adapted to drive the recorder feed drum 103 by means of clutch 112—116 and shaft section 43a as will be described in connection with Fig. 11. Keyed, or otherwise fastened, to the left-hand end of shaft 43 is a tape feed drum 45 shown in detail in Figs. 4 and 5. Drum 45 is of slightly greater width than message tape 46, and the central section 47 is annularly grooved while the peripheral surfaces are roughened, e. g., by fine line transverse grooves.

In order to hold the tape against the drum 45 so as to effect the proper feeding movement and to prevent any slippage, there are provided two endless flexible belts 48, 49, of rubber or similar material which are looped around corresponding pairs of grooved idler pulleys 50, 51, 52, 53. The pulleys 50, 52, are fastened to a common bearing hub 54 which rotates on shaft 55. Likewise pulleys 51, 53, have a common hub 56 rotatable on shaft 57 carried by wall 2.

As shown more clearly in Figs. 2 and 4, the endless belts 48 and 49 are so arranged that as they leave the front part of their cooperating pulleys, they loop towards the rear to engage the rear surface of the drum 45. In other words, the belts instead of travelling in linear paths on opposite sides of the feed drum, are deflected out of such linear path thus enabling the tape 46 to enter and leave from the same side of the drum. The dimensions of the pulleys and their positions with respect to drum 45 are such that each belt is, during the curved part of its path around the rear of drum 45, maintained in lightly tensioned contact with the drum. If desired, one or both of the pulley sets may be adjustable toward and away from the feed drum so as to adjust the tension of the belts. Preferably the two sets of pulleys are substantially contiguous with the surface of the

feed drum 45 except for the slight space provided for the rubber bands 48 and 49 which are preferably, although not necessarily, circular in cross section. In any event, it should be noted that the pulleys are of smaller diameter than the drum and the axis of rotation of the drum is offset outwardly with respect to the plane of the pulley axes. Thus in the absence of the feed drum, the rubber bands would tend to follow linear paths on opposite sides of the pulleys and preferably the axis of the feed drum is located so that while it is offset with respect to the pulleys, it nevertheless lies within the otherwise normal linear path of the belt which is indicated by the dotted line in Fig. 2. With this arrangement, the two bands maintain the tape taut against the surface of the drum throughout approximately one-half the drum circumference. While I have found that best results are obtained with this arrangement, the belts may be looped around the drum any desired angular distance.

To guide the tape, there is provided a member having side walls 68, 69, terminating at their forward upper portions in a flattened tubular inlet guide 60. This member is rigidly fastened to a flange 61 attached to wall 2. The tape outlet guide consists of a chute-like member 62 fastened to a flange 63 attached to wall 2. To strip the tape from the drum and to insure its being fed out through guide 62, the front wall of member 62 has a central struck-out tongue 64 which is slightly narrower than the groove 47 and terminates just short of the bottom of said groove. Consequently, the tape being held tautly against the drum through at least one-half the circumference thereof, when it leaves the drum it is deflected downwardly by tongue 64. At the same time, to prevent the tape sticking to the rubber belts, the rear wall of member 62 has a centrally extending tongue 65 which is slightly narrower than the space between pulleys 51, 53, this tongue extending between the pulleys to deflect the tape upwardly to insure its exit through the open end of the guide 62.

I have found that the above described manner of feeding and guiding the tape is particularly well suited where short lengths of tape are to be inserted manually for transmission. In fact, no particular skill is required to make sure that the tape is properly threaded into the machine, since even the lightest contact of the tape end with drum 45 and the belts adjacent the area where the drum first engages the belts causes the tape to be drawn between the drum and the belts in the direction of the arrows as indicated in Fig. 4. As a matter of fact, the feeding arrangement is automatically self-aligning so far as the tape is concerned, so that even if the tape is inserted into the machine with its transverse width at an angle to the axis of drum 45, the bands in cooperation with the drum 45 will automatically center the tape with respect to the drum after a short length of travel.

It will be understood that gear ratios 37—38 and 41—42 are designed so that the tape feed drum 45 rotates at a much lower speed than the scanning drum 14. Thus, if the scanning openings are approximately 0.01 inch squares, the drum 14 may be rotated at 1800 R. P. M., while drum 45 is rotated at 18 R. P. M. The effect is therefore equivalent to scanning each 0.01 inch transverse strip of the tape in twenty successive elemental areas for each one-third revolution of the scanning drum. In order to illuminate the tape, there is provided a lamp 66 mounted in a

lamp socket 67 fastened to wall 2. Preferably, lamp 66 is of the type having straight filament 66A which may be focused on the tape to an image sufficiently long to form an image on the tape reaching from the bottom to the top of the scanned letters. Positioned between the lamp and the tape on drum 45 is a conventional optical condensing system with a spherical lens 68 mounted in a bracket 69 fastened to wall 2. Bracket 69 has a vertically extending opaque wall 70 which shields the slots 16 and 33 from the direct light of the lamp. Thus tape 46 is illuminated in a concentrated band of light extending across the center portion of the tape, e. g., about one-quarter of an inch wide.

Positioned in alignment with the slots 16 and 17 and the area of the tape which is lighted by the lamp, is an objective lens 71 mounted in a bracket 72 fastened to wall 2. By this arrangement the optical system is greatly simplified and the reflected light from the message tape is collected by lens 71 and is imaged through slot 16 on the drum 7. Thus the cell 30 "sees" successive transverse strips of the tape of elemental width and the scanning perforations analyze each strip into twenty successive elemental areas. The cell electrodes 31, 32, are connected respectively by insulated electrical conductors 72 and 73 to a suitable amplifier so that the amplified response of the cell can be transmitted in any well-known manner over a communication channel.

The machine is designed to act also as a facsimile recorder or reproducer. For this purpose, there is provided the recording drum or platen 9 having three separate helically disposed knife edged ribs or threads 79, 80, 81, similar to a triple screw thread, and a cooperating recorder bar 83. By this means the electric impulses corresponding to a give message for example that illustrated by the tape of Fig. 14 are recorded simultaneously in duplicate and side by side on the recording tape 82 as illustrated in Fig. 15. For this purpose, striker bar 83 is mounted in cooperating relation with the helical ribs, so that when it is moved to striking position at any given instant, it simultaneously engages only two corresponding points of two adjacent helical ribs. The recording is effected by an inking arrangement consisting of an inking roller 120 carrying a moist inking pad 122. This inking pad is in engagement with the hard rubber doctor roller 121 which bears upon the helical ribs on drum 9.

As shown more clearly in Fig. 3, bar 83 is carried by a rigid L-shaped lever 84 which is pivotally supported on a fulcrum pin 85 fastened to wall 3. Also pivotally mounted on fulcrum pin and rigidly attached to arm 84 is an oscillating arm 86, the free end of which lies between a pair of arms 87, 88, carried by the magnetic armature 89. Armature 89 is pivoted at point 90 on the bottom of housing 91. Surrounding the shank 92 of the armature is a stationary magnetizing winding 93 whereby the end 89 of the armature is magnetically polarized. Mounted adjacent the end 89 but on opposite sides are two magnetizable cores 95, 96, with respective magnetizing windings 97, 98. Windings 97, 98, are arranged to be energized in accordance with the received facsimile signals as described in detail in application Serial No. 397,513, filed June 11, 1941. Thus, if winding 97 is energized to a greater extent than winding 98, the armature 89 is attracted to core 96, while if winding 98 is energized to a greater extent, the armature is attracted to core 95. It will be understood of course that any well-known

5 polarized oscillating armature device may be employed in place of the particular one illustrated. The circuits for the control windings 97, 98, may be arranged so that when a marking signal is on the line, the armature 89 will stay against core 95, while for spacing signal conditions on the line the armature 89 will be held against core 96.

10 Arm 86 which may be of flexible leaf-spring material, has transversely threaded therethrough an adjustable tie arm 99 whose effective length between lever 86 and lever 84 can be adjusted and locked by means of nuts threaded on arm 99 and tightened against arm 86. Arm 99 is riveted at one end to lever 84. By adjusting the effective length of arm 99, the neutral or operating position of 83 may be regulated. If it is assumed that arm 99 is locked in one place, the position of 83 will be controlled by the length of arm 99. In other words, when a marking signal 15 is received on the line, arm 86 is tilted clockwise and pushes bar 83 against the ribs 80, 81, on drum 9. During spacing, the bar 83 is pulled downwardly so that both it and the tape 82 are clear of the helical ribs 80, 81. It should also be observed that lever 84 carries a curved tape guiding plate 100 and the tape 82 extends substantially parallel to the lever throughout the greater portion of the lever length and is led off downwardly at an angle over the rounded edge 101. Likewise, the striker bar 83 is preferably rounded and the tape is taken off at a downward angle as shown in Fig. 3. Thus the tension of the tape on the end 101 can serve as a counterbalance to the load on the left-hand portion of lever 84. The direction of feeding movement of the tape is indicated in Fig. 3 by the arrows.

20 The tape after passing the bar 83 is looped over the idler roller 102 and then passes over the feed roller 103 fastened to shaft section 43a and 25 which may be constructed similarly to the feed roller 45 above described. The tape is held against the feed roller by a pressure roller 104 attached to a lever 105 pivotally mounted at 106 on wall 3. The right-hand end of lever 105 engages a compression spring 107 one end of which is seated in a cup-shaped stop 108, the other end of the spring being seated in a cup-shaped depression 109 in the lever. The tape after leaving the feed roller 103 passes through a suitable guide 30 105. It will be understood of course that the tape is fed from a suitable payoff reel and is stored on a suitable takeoff reel located in convenient positions with respect to the mechanism shown in Fig. 3.

35 The machine can be used to transmit messages and also to receive messages. However, in the event that it is desired to use only the transmitter portion, there is provided a clutch arrangement shown in detail in Figs. 1 and 11. For this purpose, the driving shaft 43 has fastened thereto a collar 110 carrying a plurality of parallel arms 111 to which are rigidly fastened the toothed clutch member 112. Slidably keyed to shaft section 43a is a collar 113 carrying a plurality of rods 114, which freely pass through a stop member 115 fastened to shaft 43a. Rigidly attached to the left-hand ends of rods 114 is a cooperating clutch plate 116. Located between members 115 and 116, is a coiled compression spring 117 whereby member 116 normally tends to engage member 112 to rotate shaft 43a. By means of a suitable lever (not shown), the members 110 and 112 may be moved to the left so as to declutch shaft section 43a from shaft 43. A pair of fingers ride in the groove of 110 and these fingers are con-

nected by a link to the switch so that when the switch is thrown to the "transmit" position, 112 and 118 are disengaged. The object of the floating arrangement of 116 and 113 with the spring 117 is to make it possible for 103 to turn freely when the tape is pulled. When 103 is rotated clockwise by pulling the tape manually, the crown ratchet wheel 116 springs out of place so as to disengage 112. It is restored by 111. Were it not for this, it would be impossible to pull out the tape manually.

All the electrical connections may be made to the various parts of the machine by means of a single terminal block 118 insulatingly mounted on the wall 2, the block 118 carrying the respective contact prongs 119 to cooperate with a corresponding plug-in member (not shown).

While one particular embodiment of the invention has been described, it will be understood that various changes and modifications may be made therein without departing from the spirit and scope of the invention. For example, the apertured slit member 16 can be dispensed with if the image of the filament 66a is focused sharply enough on the tape. This can be accomplished for example by using a simple condenser lens between the lamp 66 and the tape, the lens being "stopped" by a suitable apertured masking plate so that the tape is illuminated in a sharply focused transverse band of elemental dimensions in the direction of the tape movement. Features of the invention disclosed herein but not claimed are claimed in copending application Serial No. 439,014, filed April 15, 1942, patented February 8, 1944, No. 2,341,315.

What I claim is:

1. A tape feed and guiding arrangement for telegraph machines and the like comprising a tape supporting and feeding drum having a central circumferential recess, an endless looped flexible band having a portion of its length pressing against said drum for holding the tape against the drum, and tape guiding and stripping means comprising a pair of end plates at each end of said drum and extending slightly thereto beyond in a radial direction, an inlet tape guide connected to said plates, an outlet tape guide also connected to said plates, said outlet guide having a tongue extending into said recess to strip the tape from the drum as it emerges therefrom and having an edge in closely spaced relation to said band to strip the tape therefrom as it emerges.

2. A unitary tape facsimile transmitter and recorder machine comprising a motor having its shaft extended in opposite directions, means to generate signals in accordance with the subject matter to be transmitted including a perforated scanning drum directly fastened to one end of the motor shaft, means for recording said subject matter including a facsimile recorder platen directly fastened to the opposite end of the motor shaft, a countershaft parallel to the motor shaft,

tape feed drums carried by opposite ends of said countershaft in alignment respectively with said scanning drum and with said recording platen, a pair of endless flexible bands to hold the transmitting tape around its feed drum without interfering with the feeding movement of the tape to and from said drum, whereby said transmitting tape may be fed into and out of the machine on substantially the same side of the feeding drum.

3. A facsimile tape scanning head comprising a tape supporting and feeding drum, a pair of grooved pulley members connected to a common hub each pulley member being contiguous with the marginal ends of said drum, a pair of endless looped flexible bands surrounding said pulleys and having a portion of their surfaces engaging the tape to clamp it against said drum, a lamp having a filament disposed so as to project a scanning light band on said tape transversely of the width thereof and between the said pulleys, a perforated drum scanner mounted with its axis of rotation substantially parallel to the axis of said feed drum, a light-sensitive cell inside said scanning drum, a lens for collecting the light reflected from the illuminated light band on the tape and projecting it into the cell, and means to shield said cell against the direct light from said lamp.

30 4. A scanning head for a tape facsimile transmitter comprising a motor, a cylindrical scanning drum directly fastened to the motor shaft and having a series of scanning perforations, a tubular opaque light shield directly fastened to the 35 motor frame and surrounding said drum, said shield having a narrow light slit cooperating with said scanning perforations, and a light-proof housing for said drum and shield and attached directly to said motor frame, a photoelectric cell 40 having a supporting base fastened inside said housing said cell extending into said scanning drum, said base being adjustably fastened inside said housing to enable the photoelectric cell to be aligned with respect to said light slit.

45 5. A unitary tape facsimile transmitter and recorder machine comprising a motor having its shaft extended in opposite directions, means to generate signals in accordance with the subject matter to be transmitted including a perforated 50 scanning drum directly fastened to one end of the motor shaft, means for recording said subject matter including a facsimile recorder platen directly fastened to the opposite end of the motor shaft, a countershaft parallel to the motor shaft, 55 tape feed means carried by opposite ends of said counter shaft in alignment respectively with said scanning drum and said recording platen, and means to hold the transmitting tape around its feed drum without interfering with the feeding 60 movement of the tape to and from said drum.

AUSTIN G. COOLEY.
